UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

YOKE FOR DRAW-BARS.

1,323,260.

Specification of Letters Patent.

Patented Dec. 2, 1919.

Application filed May 6, 1918. Serial No. 232,806.

To all whom it may concern:

Be it known that I, GEORGE G. FLOYD, a citizen of the United States, and resident of Chicago, in the county of Cook and 5 State of Illinois, have invented certain new and useful Improvements in Yokes for Draw-Bars, of which the following is a specification.

This invention relates to yokes for draw bars, and to means for connecting the same to couplers.

One of the objects of this invention is to obtain and maintain maximum shoulder engagement between a draw bar yoke and 15 coupler butt under conditions where there is a variation in dimensions.

Another object is to provide a draw bar yoke being equipped in a manner to meet the requirements for successful commercial 20 operation.

These and other objects are accomplished by means of the arrangement disclosed in the figures of the drawings, in which—

Figure 1 is a plan view of my improved 25 coupler connected with the butt end of a coupler;

Fig. 2 is a side elevation, and Fig. 3 a front elevation of the same;

Fig. 4 is a fragmentary bottom plan view 30 of the means for retaining the band in locked position on the yoke arms; and,

Fig. 5 is a fragmentary detail bottom plan view of the bifurcated end of the lower yoke arm.

From the drawings it will be noted that I have provided a yoke 10 having upper and lower members 11 and 12 joined at their rear by a transverse member 13, and intermediate their ends by transverse members 14 and 15. Projecting forwardly from the transverse member 15 and forming extensions of the members 11 and 12, are arms 16 and 17 having shoulders 18 and 19, respectively. These shoulders are adapted to coöperate with shoulders 20 and 21 formed on the butt 22 of a coupler shank 23.

As a result of shrinkage of the coupler butt and of the yoke arms, sufficient engagement is not always obtained between the 50 shoulders formed on such parts. By means of my invention I obtain maximum shoulder engagement at all times regardless of shrinkage conditions. In this connection it will be noted that the space between the 55 arms 16 and 17 is sufficiently great to receive

a relatively large coupler butt, the arms 16 and 17 being capable of being sprung inwardly to a position until the shoulders of the arms and butt may have maximum engagement. To maintain this maximum engagement, I have provided a closed band 24, the upper part of which is received by a groove 25 in the forward part of arm 16 and the lower part of the closed band has formed preferably integrally therewith a threaded 60 pin 26 which occupies the opening 27 between the wings 28 of the bifurcated end of the arm 17. Associated with the threaded pin 26 is a nut 29, by means of which the band may be drawn down tightly to maintain the shoulders in locking position. It will be noted that the wings 28 are provided with projections 30, behind which is mounted a locking plate 31, which is clamped between the wings 28 and the nut 29, said 70 plate having a struck-up portion 32 which may be shifted into a locking position after the nut 29 has been squared up, as shown in Figs. 2, 3 and 4. By means of this locking arrangement, the nut is prevented from 75 turning in either direction.

In assembling the parts, the band 24 is slipped over the coupler shank and the coupler butt placed between the arms 16 and 17, after which the latter are sprung the 85 desired amount and the band is placed in the groove 25 and pin 26 in the opening 27, whereupon the locking plate and the nut may be applied for drawing the shoulders on the arms 16 and 17 and the butt 22 into 90 maximum engagement with each other and maintained in such position to meet the requirements for operating conditions.

What I claim as new is:

1. In combination, a yoke having arms 95 with shoulders thereon, one of said arms having a groove and the other an open ended slot, said arms being capable of being sprung toward each other, a solid band received by said groove and having an integrally 100 formed threaded pin received by said slot, and a threaded member for engaging said pin for drawing the arms toward each other whereby the shoulders thereof may be moved into locking engagement with an associated 105 coupler butt.

2. In combination, a yoke having arms, one of which has an opening and laterally extending projections, a band associated with said arms and having a threaded pin 110

received by said opening, a nut engaging said threaded pin for drawing the arms toward each other, and a locking plate interposed between one of said arms and said nut and being located behind said projections and having a struck-up portion for locking the nut in position.

Signed at Chicago, Illinois, this 29th day of April, 1918.

GEORGE G. FLOYD.
